UNITED STATES PATENT OFFICE

HARRY FLEISIG, OF NEW YORK, N. Y.

DESIGN FOR A DOLL'S TRUNK

Application filed April 22, 1932. Serial No. 43,575. Term of patent 7 years.

To all whom it may concern:

Be it known that I, HARRY FLEISIG, a citizen of the United States and resident of the borough of Bronx, city of New York, in the county of Bronx and State of New York, have invented a certain new, original, and ornamental Design for a Doll's Trunk, of which the following is a specification, reference being had to the accompanying drawing, forming a part thereof.

In the accompanying drawing, Fig. 1 is a front view of a doll's trunk showing my new design; Fig. 2 is a rear view; Fig. 3 is an end view and Fig. 4 is a top view.

The trunk is provided with ornamental bands at its edges as shown in the drawing. At the corners of the top and bottom por-

tions of the trunk are fastened the prong shaped ornaments as indicated. To the faces of the front, rear, top, and bottom walls of the trunk are fastened ornamental bands in imitation of straps and buckles. The ornamentalations of both the side walls are the same, and the ornamentalations of the bottom wall of the trunk are the same as the ornamentalations of the top wall thereof.

I claim:

The ornamental design for a doll's trunk, as shown and described.

Signed at the borough of Manhattan, city of New York, in the county of New York and State of New York, this 14th day of April A. D. 1932.

HARRY FLEISIG.
